UNITED STATES PATENT OFFICE

2,449,105

YARN TAKE-UP

John S. Bradley, North Attleboro, Mass., and Norman H. Smith, Pawtucket, R. I., assignors to Hemphill Company, Central Falls, R. I., a corporation of Massachusetts

Application May 23, 1947, Serial No. 750,098

6 Claims. (Cl. 66—146)

1

This invention relates to a new and useful improvement in yarn take-ups such as are used on knitting machines of the circular, independent needle type. Take-up mechanisms of the same general type are not new. One is disclosed in Patent #2,193,311. The particular advantage of this invention resides primarily in a different take-up spring through which the effective tension is varied and the take-up is adapted to the exacting requirements of fine gauge knitting such as the knitting of sheer ladies' stockings.

One form of the invention, designed for a circular, independent needle, knitting machine of the Banner type, is shown in the drawing of which:

Fig. 1 is a side elevation of a pair of take-ups and their controlling mechanism; and

Fig. 2 is a plan view of similar scope.

As many take-ups as desired may be used. They may be identical. Two are shown in the drawing, one in inoperative and one in operative position.

As shown in Fig. 1 the take-up consists of the usual light wire arm 1, identical with the similar arm 2 of the other take-up, the free end of which is bent down and terminates in a yarn guiding loop similar to loop 3 of the other take-up and through which the yarn passes on its way from the cone to the yarn lever.

The other end of arm 1 is fixed in a block 4 pivoted on a horizontal shaft 5. In the form shown block 4 is slotted as at 6 so that the take-up arm 1 can be slid into it sideways after which it is fixed in position by set screw 7. Extending rearwardly of block 4 is a tail 8 which may be integral with arm 1. This tail is offset laterally of arm 1 as best shown in Fig. 2. Below tail 8 is a spring arm 9 which is substantially flat, one end of which has an opening 10 therein through which tail 8 passes.

On the frame 11 of the take-up is pivoted, as at 12, a rocker 13 to which the spring 9 is secured by a cover plate 14, which is held by screws 15 to bind the spring between the cover and the rocker. Therefore, the spring 9 is pivotable on the frame at 12 with the pivotal movement preferably in a vertical plane and limited in the up direction by an adjustable set screw 16 mounted in a bracket 17 and in the down direction through the holding action of the yarn exerted through the arm 1.

Normally, the downward pull of the spring 9 causes the tail 8 to be pulled down, pivoting the arm 1 upward against the resistance of the yarn. In so doing, the foot end of spring 9 slides along

2

tail 8. In this way, the effective length of tail 8 with respect to shaft 5, upon which the take-up arm 1 is pivoted, is varied which results in automatic changes of leverage.

As the spring moves downwardly, its effective strength becomes progressively less, but its longitudinal leverage on the tail 8 allows this decreasing spring strength to exert a substantially constant or increasing force upon the arm 1. The spring 9 is sufficiently rigid lengthwise so that as the arm 1 is swung about the pivot 5 through the tightening or loosening of the yarn, the foot of the spring 9 moves along the tail 8 to provide the desired leverage variation. This lengthwise rigidity is important in that it provides positive and smoothly progressive movement of the spring along the tail 8, and leverage changes are made smoothly.

By altering the curvature or shape of tail 8, the effect of the spring 9 can be additionally adjusted so that changes in the rate or character of leverage variation may be suited to requirements.

Further variations in adjustment are possible through the elongated screw openings 17' in the spring 9. The screws 15 may be loosened and the spring 9 adjusted lengthwise within the limits defined by the openings 17' and the screws 15 therein. Also, the pivot shaft 12 may be adjusted in the body 11 by means of the elongated opening 18 in the frame. The pivot shaft 12 extends through this frame opening and is secured by nut 19 on the end of the shaft 12 after it has been adjusted toward or away from the pivot 5 of arm 1.

Thus the effective length of the spring 9, its effective strength and the adjusted position of the spring opening 10 with respect to tail 8 may be varied, as desired, within the limits of the adjustments set forth above, using these adjustments either singly or in combination to get the desired spring position, effective strength and leverage relation.

The spring 9 is an L-shaped flat spring member with the top of the L secured to the rocker 13 and the foot of the L having an opening 10 therein. The spring 9 resists the downward swinging action of arm 1 as it is pulled down by the yarn. In association with take-up arm 2, the second flat spring 20 is shown (Fig. 1) in up-sprung position and exerting its strongest inherent downward pull. In the drawing, the position of spring 9 indicates a minimum of downward pull since the spring lies unflexed. Springs 9 and 20 are identical in form and operation

and are shown in different positions for purposes of illustration.

Suitable devices for making the take-up inoperative when desired, and for clamping the yarn to prevent excess feeding from the cone, may be used with the take-up assembly of this invention. In former take-ups the spring had to be strong enough to lift the take-up arm quickly to its highest position, say 60 degrees or more above the horizontal. As a result, when the take-up arm moved down the tension of the spring increased constantly and unavoidably became too great within the working range of the take-up while knitting was being carried on.

When knitting extremely sheer fabric such as a lady's stocking, very small errors in method, particularly those affecting the yarn, produce very noticeable fabric defects. It has been found that the tensioning effect of spring 9 upon take-up arm 1 should be substantially uniform throughout the movements of the take-up and, in some instances, should be lighter when the take-up is down than when it is raised so that the take-up will exert a negligible or minimum effect upon the yarn during knitting.

Often it is desirable that the lifting effect of spring 9 upon arm 1 should increase as the arm rises in spite of the decreasing actual tension of the spring. All of these things can be accomplished by the hook-up described above through the proper shaping and proportioning of arm 1, tail 8 and spring 9. Since an infinite variety of conditions are met in the knitting of various fabrics these matters must and can be left for determination by those skilled in the art. The manner in which a take-up of this character operates is otherwise too well-known to require further description.

The springs 9 and 20 are described as flat, and it is intended that this shall mean leaf type springs, and that a resilient rod or wire shall come within the scope of this definition and invention.

We claim:

1. A yarn take-up for a knitting machine which includes a swingable take-up arm and a leaf spring member for swinging said arm, said spring comprising a source of energy which is greatest when said arm is down and which decreases progressively as said arm rises, said spring

having an end thereof in variable leverage relation with said arm, whereby variations in the applied force of said spring are accompanied by simultaneous inverse variations in its effective force upon said take-up arm.

5. In a knitting machine, a pivoted yarn take-up arm, a tail member for said arm, and a leaf spring associated with said tail in variable leverage relation therewith, whereby variations in the applied force of said spring are accompanied by simultaneous inverse variations in its effective force upon said take-up arm.

10. In a knitting machine, a pivoted yarn take-up arm, a tail member for said arm, and a leaf spring having one end pivoted and the other riding on said tail in varying leverage relation therewith to counteract varying forces in said spring.

15. In a knitting machine, a pivoted yarn take-up arm, a tail member for said arm, a leaf spring having one end pivoted and the other riding on said tail in varying leverage relation therewith to counteract varying forces in said spring, and means for adjusting the pivot of said spring 20 to change its distance from said take-up arm pivot.

20. A yarn take-up for a knitting machine which includes a pivoted take-up arm, a tail member for said arm, a leaf spring riding on 25 said tail in varying leverage relation therewith to counteract varying forces in said spring, and means for changing, by adjustment, the effective length of said spring.

25. In a knitting machine, a pivoted take-up arm, a tail member for said arm, a leaf spring having one end pivoted and the other riding on said tail in varying leverage relation therewith to counteract varying forces in said spring, and an adjustable stop for limiting the pivotal 30 movement of said spring.
